UNITED STATES PATENT OFFICE.

WILBUR MARVIN CARPENTER, OF ST. LOUIS, MISSOURI.

SHORT-HAND MACHINE.

SPECIFICATION forming part of Letters Patent No. 453,233, dated June 2, 1891.

Application filed July 30, 1884. Serial No. 139,196. (No model.)

To all whom it may concern:

Be it known that I, WILBUR MARVIN CARPENTER, of St. Louis, Missouri, have made a new and useful Improvement in Short-Hand Machines, of which the following is a full, clear, and exact description, reference being had to the annexed drawings, making part of this specification, in which—

Figure 1 is a plan of a machine having the improvement; Fig. 2, a vertical longitudinal section showing one of the keys depressed; Fig. 3, a similar section, the key being elevated; Fig. 4, the impression made by all the keys when simultaneously depressed; Fig. 5, the rear end elevation of the machine; Fig. 6, an elevation similar to that of Fig. 5, but showing the inking-ribbon device shifted to wind the ribbon in the opposite direction; Fig. 7, a plan, upon an enlarged scale, of the rear end of the machine; Fig. 8, a plan of the marker-guide closed; Fig. 9, a plan of the marker-guide opened; Fig. 10, a side elevation of the rear end of one of the groups of keys, the stop, the spacer-bar, and the inking-ribbon shifter being in section; Fig. 11, a view in perspective showing the rear end of one of the sets of keys; and Fig. 12 is a plan showing how the spacer-bar is attached to the rear end of the machine.

The same letters of reference denote the same parts.

The object of this invention is to print or write with great rapidity upon a strip of paper phonographic characters representing articulate sounds and combinations of sounds, syllables, words, &c., and by a new and peculiar arrangement and combination of the keys and markers to enable the operator to form or print several different characters by one stroke or movement of the hand or hands.

The improvement is carried out by means of three similar sets of keys, the keys of each set being so constructed and grouped that one, two, or three of them can be struck with a single finger and all of them with two fingers, and the several sets of keys being so grouped that any three combinations of keys in the three sets, respectively, can be struck simultaneously and with six fingers—that is, there is a set of keys at each side of a central set, and the set of keys at the right can be operated by any two or more fingers of the

right hand, the set of keys at the left by any two or more fingers of the left hand, and the middle set can be operated by the thumbs and forefingers of both hands. The keys in each set are provided, respectively, with finger-plates, and the finger-plates are so relatively arranged and are in such proximity to each other that any adjoining two or three of them can be simultaneously pressed with a single finger. To this end there is a central finger-plate surrounded by a group of four finger-plates, and this group in turn is surrounded by a single finger-plate. The central finger-plate can be operated by itself by pressing the finger upon it, so that it shall not bear upon any of the marginal finger-plates, and any one of the outlying finger-plates in the set can be similarly separately operated; but when it is desired to operate two keys in the set simultaneously the finger is adjusted to bear upon the abutting edges of the finger-plates of those two keys, and when three keys are to be moved at the same time the finger is adjusted to bear upon the abutting edges of the finger-plates of those three keys. The central finger-plate in each set can thus and with a single finger be struck in connection with any one of the four finger-plates which jointly immediately surround the central finger-plate, and any adjoining two of the four finger-plates which jointly surround the central finger-plate can be struck in connection with the central finger-plate or in connection with the outermost finger-plate of the set. Thus with two fingers all the finger-plates of a set of the keys can be struck and a simple or composite symbol, mark, or character made, and with six fingers the entire key-board of eighteen keys is commanded, and two or three simple or composite symbols, marks, or characters can be made.

A complementary feature of the improvement is providing the keys with markers and relatively constructing and arranging the keys and markers so that two or more keys of a set of keys can be operated to produce a composite symbol, letter, character, or mark, and so that two or more keys in each set of keys can be operated to produce in line with each other or in juxtaposition to each other two or more separate symbols, letters, characters, or marks.

Minor features of the improvement are the mode of constructing the marker-guide and the device for shifting the inking-ribbon.

A B C, Fig. 1, represent the three sets of 5 keys, the set A having the keys $a a' a^2 a^3 a^4 a^5$, the set B having the keys $b b' b^2 b^3 b^4 b^5$, and the set C having the keys $c c' c^2 c^3 c^4 c^5$.

D E F represent the three sets of finger- 10 plates respectively belonging to the three sets of keys, the set D being made up of the central finger-plate d , the four finger-plates $d' d^2 d^3 d^4$, which jointly surround the finger-plate d , and the outermost finger-plate d^5 , which extends around the four finger-plates $d' d^2 d^3 d^4$, 15 the set E being similarly composed of the finger-plates $e e' e^2 e^3 e^4 e^5$ and the set F being similarly composed of the finger-plates $f f' f^2 f^3 f^4 f^5$.

The various keys are adapted to be vibrated, 20 for this purpose being pivoted at G, Figs. 2 and 3, and made to bear upon the elastic bearing H, which acts to restore the keys after being depressed. When but a single key is to be depressed—say the key a^2 —the finger 25 is applied only to the finger-plate d^2 belonging to that key. When two keys—say the keys $a^2 a^3$ —the finger is applied to the finger-plates $d^2 d^3$, and when three keys—say the keys $a a' a^2$ —the finger is applied to the finger- 30 plates $d' d' d^2$. It is apparent that when but one finger-plate is to be moved the finger can be applied to any part of it; but when two finger-plates—say the finger-plates $d' d^2$ —are to be moved by a single finger the finger 35 must be applied so as to bear upon both finger-plates, and this obviously requires the finger to be applied to the abutting edges of those finger-plates—that is, at x , Fig. 1—and when three finger-plates—say finger-plates $d' d' d^2$ —are to be moved the finger must be applied where those three finger-plates meet—that is, at the point x' , Fig. 1. As is seen, 40 the central finger-plate d can be struck in combination with any one or with any adjoining two of the four finger-plates $d' d^2 d^3 d^4$. The outermost finger-plate d^5 can also be struck in combination with any one or with any adjoining two of the finger-plates $d' d^2 d^3 d^4$, for the finger can be applied to the finger- 45 plate d^5 at any point thereon. It results from this that sixty-three single and composite symbols can be produced with the six keys $a a' a^2 a^3 a^4 a^5$. A similar result is obtained with the B and with the C set of keys. The 50 keys are each provided with a device termed a “marker,” by means of which the movement of the key is caused to register a mark upon any suitable surface, such as a ribbon of paper. These markers are represented at I, Figs. 2, 3, 55 60, 6, 10, and 11. The marker consists substantially of an arm i , which projects from the key, and is shaped to form or is provided with a type i^2 , with which the mark is made. The working of the keys and finger-plates in the manner described does not necessitate the adoption of 65 particular marks. Any desirable marks may be assigned to the keys $a a'$, &c., respectively;

but to carry out the improvement the keys and markers are so combined and constructed as to enable the several markers belonging to a set $a a'$, &c., of keys to not only severally register single marks, but also in combination to register composite marks—that is, each marker can be used by itself or in combination with any other marker of the set. The marks I prefer are shown in Fig. 4. The set is composed of four straight lines $J J' J^2 J^3$ and two curved lines $J^4 J^5$. These marks are made, let it be assumed, by the keys $a a' a^2 a^3 a^4 a^5$, respectively. The markers I are relatively adjusted, substantially as shown in Fig. 11, to cause the marks $J J'$, &c., to be inclined, relatively arranged, and grouped, as shown in Fig. 4. When all the keys $a a'$, &c., are struck simultaneously, all 70 the marks $J J'$, &c., appear as in the middle third portion of Fig. 4. When but a portion of the keys—say the keys $a a'$ —are struck, only the marks $J J'$ appear. The marks, however, always appear in the same relative 80 position, whether two, three, or more keys of the set are struck. Therefore any one of the marks $J J'$, &c., can be combined with any other or others of the set to form a composite mark. These composite marks, like the simple marks, can represent letters, &c., and by means of the simple and composite marks thus produced some sixty-three different letters, &c., in practice can be represented. The B set of keys can be similarly operated 90 to produce a similar set of marks, which are represented in the lower third portion of Fig. 4, and the marks produced by the C set of keys are represented in the upper third portion of Fig. 4. By means of the three sets of 95 marks three different letters, &c., can be produced simultaneously by the machine and in line with each other.

K represents what may be termed the “marker-guide.” This guide is perforated 100 vertically to admit the arms i of the markers. The peculiarity of the guide is making it in parts $k k' k^2 k^3$, Figs. 8 and 9, which can be closed together, as in Fig. 8, or opened apart, as in Fig. 9. The object of this is to enable 105 the markers to be readily reached and adjusted. When the guide is to be used, it is closed, as in Fig. 8, and when the markers are to be adjusted the guide is opened, as in Fig. 9. The parts $k k'$ are preferably hinged together at k^4 , and the bolt k^5 , when the parts are closed, secures their free ends together. The marks are registered on a paper ribbon 110 L, Figs. 5 and 6. The mechanism for holding and moving this ribbon is of the ordinary character, the keys $a a'$, &c., in their downward movement depressing the forward end m of the spacing-lever M, and this lever in turn actuating, by means of the hook N and ratchet N' , the shaft N^2 of the drum N^3 , 115 said drum turning the tension-roll (not lettered) immediately below by friction and serving to feed out the paper ribbon, (not shown, as it is of common form,) which is to 120 125

pass between these as it is unwound from the delivery-roll, which is shown at the upper right-hand corner of Fig. 1. An inking-ribbon O, Figs. 5 and 6, extends above the paper ribbon, being carried around the drums $o' o'$, Figs. 1, 5, 6, and 7. The rolls are actuated by hooks $o^2 o^3$, attached to the spacer-bar M and engaging with the ratchets $o^4 o^5$ on the drums $o' o'$, respectively—that is, (and this is the peculiarity of this portion of the machine,) the hooks $o^2 o^3$ are adapted to be put alternately into engagement with the ratchets $o^4 o^5$ as follows:

P represents what may be termed the "inking-ribbon spool-pawl shifter." It is in the form of a slide and adapted to be slipped to and fro a short distance transversely, the space-bar M being pivoted or adapted to have a slight shifting movement sidewise in the machine beneath the keys $a a'$, &c. The shifter by some suitable means is in engagement with the spacer-bar, to which the hooks $o^2 o^3$ are attached. When this inking-ribbon spool-pawl shifter is shifted one way in the machine, the hook o^2 is brought into engagement with the ratchet o^4 , and the other hook o^3 is disengaged from its ratchet o^5 and the inking-ribbon is moved accordingly; but when the pawl-shifter is shifted in the opposite direction the hook o^2 is disengaged from its ratchet and the hook o^3 is engaged with its ratchet, and the inking-ribbon now moves in the reverse direction.

Q represents a vertically-adjustable stop to limit the upward vibration of the keys. The outermost finger-plate in each set of finger-plates is liable to be racked upon its key when pressed upon one side. To better sustain it, therefore, this finger-plate is attached to the arms R R, which are pivoted at $r r$ and move similarly to the keys $a a'$, &c.

S represents the spacer-key. It is constructed and operated in the ordinary manner. It is supported on the arms R' R'.

The arms R R' are not in any way fastened to the spacer-bar M, but merely rest upon it, and they do not interfere with the transverse movement of the spacer-bar. To provide for the shifting movement of the spacer-bar, its ends are pivoted to the frame of the machine at its rear end as follows: Two standards $m m$ are attached to the base of the machine, and the ends of the spacer-bar are let into slots at the top of the standards. The slots are wide enough to allow the spacer-bar sufficient play from side to side to bring the spool-pawls into engagement with the ratchets alternately. The spacer-bar ends are held in the slots by pins and so that the spacer-bar can be shifted laterally. The elastic bearings, which serve to restore the spacer-bar to its original position, are of rubber or similar material, and when the shifter P is pushed or pulled the spacer-bar is shifted laterally over the base of the machine for the purpose described. I desire to be understood as not confining myself to this particular method of moving the

inking-ribbon and shifting the ribbon-spool pawls, this being merely an incidental part of the machine, and any other suitable apparatus similar to what is in common use may be employed in the place of the apparatus herein described. The spacer-bar, for instance, may be of spring-steel, whereby it would have sufficient play without requiring to be moved to and fro in the standard-slots. 75

Among other special features of the present machine are the following: The manual or key board is placed on the keys between the pivots upon which they turn and the free or marker ends of the keys. The keys therefore strike downward and print the characters upon the upper surface of the paper ribbon, which, as may be seen, moves from right to left in front of the operator, and the writing 80 may therefore be read as the paper ribbon moves out from under the inking-ribbon. The characters formed also have a peculiar arrangement, both in respect to each other and with reference to the key-board, whereby 85 the several characters may be more easily learned than any others in use, and when learned they may be more easily selected to form combinations, because the vertical mark corresponds to the central finger-plate d , the 90 horizontal mark to the exterior plate, and the oblique marks to the four plates surrounding the central plate. The group of markers therefore is similar to the group of finger-plates, and, if necessary, may correspond further by 95 placing the horizontal mark entirely above or below the oblique marks, the only objection to this arrangement being that it would be necessary to widen the paper ribbon. 100

I am aware that groups of arbitrary marks 105 arranged to represent characters when used singly or in combination are commonly employed in stenographic machines. Therefore no more is claimed in the present instance than the particular form and arrangement herein shown.

I claim—

1. The combination, in a writing-machine and with the corresponding keys and markers, of the central finger-plate d , the finger-plates $d' d^2 d^3 d^4$, jointly surrounding the central finger-plate, and the finger-plate d^5 , extending around the finger-plates $d' d^2 d^3 d^4$, substantially as described. 115

2. The marker-guide made in parts $k k'$, 120 &c., to open, as described, in combination with the marker-arms, as described.

3. In a writing-machine, a group of finger-plates consisting of an encircling finger-plate d^5 and a series of finger-plates inclosed thereby, adapted to be operated separately or in conjunction with the encircling plate, the said plate d^5 being continuous, substantially as described. 125

4. In a key-board of a writing or other machine, the combination of a central finger-plate, as d , a series of finger-plates $d' d^2$, &c., arranged jointly around and abutting on the central plate and on each other, and an ex- 130

terior surrounding plate, as d^5 , so that any plate d' d^2 , &c., of the series or any two adjacent ones may be depressed with a single finger jointly with either the exterior plate or the central plate, substantially as described.

5. In a stenographic writing or other machine, the set of markers composing the group I, said set consisting of four straight and two curved type-faces or markers, arranged and 10 adapted, as herein shown, to register distinct characters when used singly or in combina-

tion, through the means described and shown, two of said straight markers being arranged at right angles, with one resting upon the center of the other, and the remaining four markers being arranged obliquely about and near to those at right angles, substantially as shown in Figs. 4 and 11.

WILBUR MARVIN CARPENTER.
